UNITED STATES PATENT OFFICE.

CHARLES P. SCHAEFER AND ROBERT M. BROWN, OF CHICAGO, ILLINOIS.

CONSTRUCTION TIE.

Application filed October 23, 1924. Serial No. 745,460.

To all whom it may concern:

Be it known that we, CHARLES P. SCHAEFER and ROBERT M. BROWN, citizens of the United States, residing at Chicago, in the county of Cook and State of Illinois, have invented certain new and useful Improvements in Construction Ties; and we do hereby declare the following to be a full, clear, and exact description of the invention, such as will enable others skilled in the art to which it appertains to make and use the same.

This invention relates to building construction, and more particularly to structures of concrete or the like, having an outside veneer of brick, tile or other building blocks.

The object of the invention is to provide suitable means for securing or binding the structural elements or blocks to a surface of concrete or the like.

Another object of the invention is to provide means for tying a veneering of tile or other suitable blocks to the main building wall in a strong and simple manner so that the said building blocks will not have to be defaced or be made in any other manner than of a regular type.

Another object of the invention is to provide an improvement upon our prior structure shown in Patent No. 1,472,194 dated October 30, 1923, of which we are joint owners, and to simplify and cheapen the structure whereby the key strips are anchored in the dove-tail groove of the wall or main portion of a building wall, such as columns or other massive and strong elements thereof, and to obviate the necessity of providing under cuts or grooves extending continuously throughout the height thereof or dove-tail channel members of metal co-extensive therewith and extending throughout the length of the grooves, thus providing a more economical construction and preventing the dropping of the key-strip or tie-elements in the channel members and thus not interfere with the proper function of the device. With this in view, we provide sockets or channel members with closed ends which are provided at spaced intervals throughout the height of the wall, the sockets and closed ends being preferably produced from a single blank of material such as sheet metal, cast or otherwise.

Other objects will appear as the description proceeds.

In the accompanying drawings, which constitute a part of our application:

Fig. 1 is a front elevation of a section of a building wall showing the masonry-attaching means in position.

Fig. 2 is a horizontal sectional view taken on the line 2—2 of Fig. 1.

Fig. 3 is an enlarged vertical section view taken on the line 3—3 of Fig. 2.

Fig. 4 is a perspective view of the slotted plate or member.

Fig. 5 is a perspective view of the improved tie or key strip which co-operates with the plate illustrated in Fig. 4.

Fig. 6 is a sectional perspective view of the socket or channel member, showing one end thereof.

Fig. 7 is a horizontal sectional view corresponding to Fig. 2 and showing another fastening means for building blocks and the like or masonry, especially at a joint between adjacent blocks or sections.

Fig. 8 is a perspective view partly in sections and partly broken away and in dotted lines showing a combined tie member and key strip for use in connection with a veneering or facing of bricks or the like.

Fig. 9 is a perspective view of a combined tie member and key strip adapted for use in connection with masonry or building blocks in another form of the invention, and

Fig. 10 is an enlarged vertical sectional view corresponding to Fig. 3 showing the device illustrated in Fig. 9 applied.

Like character of reference are used throughout the following specification to designate corresponding parts.

Wall 1, of concrete or other suitable material and of suitable construction constituting the whole or main portion of a building wall and provided with columns or other massive and strong elements, adjacent to thinner parts as illustrated, is provided with vertical or perpendicularly extending spaced dove-tail grooves 2, which are wider at their inner ends or bottoms than at the entrance or throat portions thereto. In order to strengthen these grooves, they are lined with dove-tail sockets or channel members 3, preferably formed of metal, which are provided with sides 3^a bent from the central bottom portions thereof in the same direc-

tion toward each other to provide converging side portions having curved edges or flanges 3^b forming shoulders adapted to conform to the corners or edges of the grooves 2 in the wall 1, as fairly shown in Figs. 1, 2 and 6 of the drawings. The sockets or channel members 3 are preferably formed of blanks or sections of sheet metal, preferably galvanized, and with ends 4 produced by severing the corners of the blanks and turned at right angles between the sides of the socket to prevent the latter collapsing inwardly toward each other, thereby strengthening and reinforcing the sockets or channel members, which are set into the concrete wall and extend flush with the same, either by molding the wall material around the sockets or otherwise. The ends 4 are shaped to conform to the dove-tail crossed section 20 of the sockets or channel members as shown.

A plate or member 5 is provided with the rearwardly extending spaced or top and bottom flanges 5^a and reduced central lugs 6, said flanges stiffening the plate and straddling or spanning the sockets and the lugs being adapted to enter the forward ends of the dove-tailed grooves 2 or the sockets or channel members 3 set therein, in the concrete wall 1. A slot 7 is formed transversely 30 through the plate 5 and having closed ends as shown in the preferred construction is adapted to receive the tie or key strip 8, which has formed integrally theron, a rearwardly extending dove-tailed portion 9, which is adapted to extend into the groove 2 or the socket 3 between the sides of the latter, and to fit snugly therein. Obviously the portion 9 is inserted and turned when engaged in the groove or socket. The strip 8 is provided with one or more, preferably two openings 10, one of which is adapted to receive one end 11^a of a substantially U-shaped tie-iron 11, which latter is disposed in an inverted position when engaged in an opening 10 to contact with the plate 5 as clearly shown in Figs. 2 and 3 of the drawings. The opposite end 11^b of the said tie-iron 11 is adapted to seat in an opening 12, in the tile-blocks or masonry 13 and produced in the form of sockets in the tops of the latter at the points where necessary, so that the lugs will be readily held in position adjacent the concrete wall, and may be anchored therein by concrete 14 or otherwise. Obviously, a plurality of such tie-members or irons may be employed. The device shown is adapted for two.

From the foregoing description it will be apparent that the plate member 5 will be readily held against the concrete wall 1, due to the rearwardly extending lugs 6, which enter the channel or groove 2 or the socket held therein. The portion 9 of the key strip 8 snugly fitted in the groove 2, is prevented 65 from turning by reason of the lugs 6, slot 7

end 11^a entering said slot between 5 and 8.

Obviously, the dove-tail sockets or channel members 3 may be cast or otherwise formed and the ends closed in any suitable manner to strengthen and reinforce the 70 same. Moreover, the ends 4 may be welded or otherwise joined in molecular union with the sides 3^a thereof, including the converging side portions and the curved edges or flanges 3^b forming shoulders as heretofore 75 specified.

In Fig. 7 of the drawings, openings 10' corresponding to the openings 10 are provided in the plate constituting the tie or key strip 8', and these may be arranged in staggered relation or in a line as desired to receive inverted U-shaped tie-irons or strips 11' to connect the blocks of the masonry or facing wall 13 at a joint as shown in this figure, as described in connection with the 80 tie-iron 11. When the openings 10 are arranged as in Fig. 5, the tie-irons 11' will clear one another where engaged with the plate 8 or key strip formed thereby. Obviously, the tie-irons may be made of the required length and are anchored and in semi-circular cut-outs in the top portions of the adjacent building blocks, monoliths or the like in line therewith. Otherwise, the construction in this form of the invention is 95 the same as that described in connection with Figs. 1 to 6 inclusive.

In Fig. 8 of the drawings a combined tie and key strip or plate 15 is shown, which is adapted for use in connection with brick 100 walls or similar facings or veneering. The brick wall is shown at 16 and the plate 15 has a dove-tailed end 17 to engage the dove-tailed groove or socket 2 or 3 as previously described, and the enlarged end of this 105 wedged-shaped plate is provided with an opening as indicated at 18 and an upturned flange or lip 19 at one edge, preferably the outer edge, to be locked in the mortar or other binding between the brick or the like. 110 The mortar will also pass into the slot or opening 18 and when hard, will firmly anchor and connect or tie the parts together against separation.

In the construction shown in Figs. 9 and 115 10 of the drawing, a tie or key strip 20 is employed having a downturned outer end or flange 21 to be anchored in the wall or block as are the tie-irons 11 and 11' and is covered with mortar while the dove-tail end 120 22 is held in the dove-tailed groove 2 or socket 3, as heretofore described. The plate or tie members may be flat sheet metal or otherwise. Thus it will be understood and seen that the tile veneering will be positively held in position adjacent the concrete wall of the building structure and that the tile blocks will not have to be broken or special forms of blocks be required in order to use the anchoring means.

It will be understood that the anchoring grooves and anchoring means may be positioned in any place desired in the building walls so that the maximum of strength and efficiency may be had. Furthermore, by providing the sockets or channel members as spaced points, economy in the use of metal and in the construction over the use of continuous vertically extending grooves or 10 channel members as provided in the construction shown in our prior patent, or the dropping of the tie or key members engaged therewith and with the veneering wall will be prevented. This also provides for facility in the construction and the tie members 15 cannot drop.

Many minor changes in detail of construction may be resorted to without departure from the spirit of the invention. 20 Of course, it is to be understood that the socket or channel members 3 are nailed or otherwise secured on a form for producing a concrete wall, so that when the concrete is poured and set or hardened, the sockets 25 or channels, reinforced as described with metal, will be produced.

Having thus described our invention what we claim as new and desire to secure by Letters Patent in the United States is:

30 1. In a building structure, the main wall element having dove-tail grooves, having in cross section a wider interior than entrance, a veneer of building blocks, plates provided with rearwardly extending, spaced lugs, said 35 lugs adapted to set in said grooves, key strips extending through said plates into said grooves, and means for attaching said building blocks to said key strips.

2. In a building structure, a main wall 40 having dove-tail grooves having in cross section a wider interior than entrance, a veneer of building blocks, plates or members having rearwardly extending spaced lugs, said lugs being adapted to engage a 45 seat in said grooves, said plates being provided with transversely extending slots, key strips extending through said slots in said plates and detachable means connecting the outer ends of said key strips with said 50 building blocks.

3. In a building construction, a main wall 55 having dove-tail grooves, linings in said grooves, plates or members having integrally formed rearwardly extending spaced lugs, said lugs adapted to seat in said grooves, said plates being provided with transversely 60 extending slots, key strips provided with dove-tail portions, adapted to pass through said slots in the said plates and to seat in said dove-tail groove or notches, said strips

being provided with an opening in the forward end and means for connecting said strips with said building blocks.

4. A construction tie, comprising a 65 slotted plate having spaced rearwardly extending lugs and a flat key strip adapted to extend through said slotted plate substantially as described.

5. A construction tie comprising a slotted plate provided with rearwardly extending spaced lugs, and dove-tail key strips adapted to extend through said slotted plates, and a substantially U-shaped tie-iron detachably secured to said key strips. 70

6. A building construction comprising a 75 main supporting element, dove-tail grooves in the surface thereof, and lining in said grooves, plate provided with means for engaging with said grooves, tie-strips having an enlarged front portion and dove-tail rear portion, said dove-tail portions of said tie-strips being adapted to extend through said plate or members, and substantially U-shaped tie-irons detachably connected with 80 the forward ends of said key strips. 85

7. In a building structure, a main wall provided with dove-tail grooves spaced apart, sockets in said grooves, said grooves and sockets having a wider interior than entrance, plates having dove-tail portions engaged in said sockets, and inverted U-shaped tie members engaged with the plate and adapted to connect to a veneering wall. 90

8. A construction tie comprising a slotted plate provided with rearwardly extending spaced lugs, a dove-tail strip adapted to extend through said slotted plate a socket member adapted to seat in a groove in a wall to receive said lugs and dove-tail portion of the key strip, and a tie-member having ends adapted to engage said key strip and a veneering wall to be anchored to a main wall carrying the socket members. 95

100 9. A construction tie, comprising a plate having rearwardly extending lugs, adapted to enter a groove in a building wall with a restricted entrance portion, a key strip having a portion engaged through said plate and retained in said groove by conformation with the cross section thereof when turned at right angles to the length thereof, said plate having an aperture, and a tie member having angularly directed ends, one end of which is adapted to extend into the aperture and the other to be imbedded in a socket of 105 a veneer wall. 110

In testimony whereof we affix our signatures.

CHARLES P. SCHAEFER.
ROBERT M. BROWN.
